ACOUSTICAL TILE

Melvin L. Olson, Shelton, Wash., assignor to Simpson
Timber Co., Seattle, Wash., a corporation of Wash-
ington

Filed Jan. 13, 1958, Ser. No. 49,242

Term of patent 14 years

(Cl. D18—2)

—. 1.

—. 2.

FIG. 3.

FIG. 4.

FIGURE 1 is a top plan view of an acoustical tile showing my new design;

FIGURE 2 is an end view thereof;

FIGURE 3 is an enlarged fragmentary plan view of the lower right hand corner portion of the tile of FIGURE 1, and

FIGURE 4 is a sectioned view of the tile taken along the lines 4—4 of FIGURE 3.

I claim:

The ornamental design for an acoustical tile, as shown.
